[57] CLAIM

The ornamental design for a circuit breaker, as shown an described.

DESCRIPTION

FIG. 1 is a front elevational view of a circuit breaker showing my new design;

FIG. 2 is a left side elevational view thereof;

FIG. 3 is a right side elevational view thereof;

FIG. 4 is a rear elevational view thereof;

FIG. 5 is a top plan view thereof;

FIG. 6 is a bottom plan view thereof; and,

FIG. 7 is a front elevational view of a circuit breaker showing a second embodiment of the design. The plan views and the other elevational views are the same as the first embodiment except for the appearance of the lever.

Fig. 1.
